UNITED STATES PATENT OFFICE

155,147

DESIGN FOR A TOWEL HOLDER

Samuel Goldreich, Middletown, Conn., assignor
to Raymond Products, Inc., Middletown, Conn.,
a corporation of Connecticut

Application March 26, 1948, Serial No. 145,387

Term of patent 7 years

(Cl. D33—16)

To all whom it may concern:

Be it known that I, Samuel Goldreich, a citizen of the United States, residing at Middletown, county of Middlesex, and State of Connecticut, have invented a new, original, and ornamental Design for a Towel Holder, of which the following is a specification, reference being had to the accompanying drawing, forming part thereof.

Fig. 2 is a plan view.

Fig. 3 is a front view.

I claim:

The ornamental design for a towel holder, as shown.

SAMUEL GOLDREICH,
